United States Patent Office

Des. 191,363
Patented Sept. 19, 1961

191,363

ROLLER SKATE

Daniel S. Williams, 394 Spruce St., Pottstown, Pa.

Filed Nov. 22, 1960, Ser. No. 62,925

Term of patent 14 years

(Cl. D34—5)

Fig. 5

Fig. 6

FIGURE 1 is a side elevational view of the roller skate showing my new design.

FIGURE 2 is a top plan view thereof.

FIGURE 3 is a front elevational view of the roller skate showing my new design.

FIGURE 4 is a bottom plan view of the roller skate.

FIGURE 5 is a sectional view taken on the line 5—5 of FIGURE 1.

FIGURE 6 is a rear elevational view of the roller skate showing my new design with the leg strap shown fragmentarily for convenience of illustration.

FIGURE 7 is a sectional view taken on the line 7—7 of FIGURE 1.

I claim:

The ornamental design for a roller skate, as shown and described.
